DESIGN FOR A LISTING CALCULATOR

Loring P. Crosman, South Orange, N. J., assignor
to Monroe Calculating Machine Company,
Orange, N. J., a corporation of Delaware

Application December 22, 1941, Serial No. 104,789

Term of patent 14 years

To all whom it may concern:

Be it known that I, Loring P. Crosman, a citizen of the United States of America, residing at South Orange, in the county of Essex and State of New Jersey, have invented a new, original, and ornamental Design for Listing Calculators, of which the following is a specification, reference being had to the accompanying drawing, forming part thereof.

Figure 1 is a perspective view of a listing calculator, showing my new design.

Figure 2 is a detail perspective view, on an enlarged scale, of one of the key heads thereof.

The dominant features of my design are shown in solid lines on the drawing.

I claim:

The ornamental design for a listing calculator, as shown and described.

LORING P. CROSMAN.
